UNITED STATES PATENT OFFICE

ALOIS A. RITTER, OF RACINE, WISCONSIN, ASSIGNEE TO HARTMANN TRUNK COMPANY, OF RACINE, WISCONSIN, A CORPORATION OF WISCONSIN

DESIGN FOR A TEXTILE FABRIC

Application filed December 24, 1928. Serial No. 29,401. Term of patent 7 years.

To all whom it may concern:

Be it known that I, ALOIS A. RITTER, a citizen of the United States, residing at Racine, in the county of Racine and State of Wisconsin, have invented a new, original, and ornamental Design for Textile Fabric, of which the following is a description, reference being had to the accompanying drawing, forming part thereof.

In the drawing, the figure is a plan view of a piece of the textile fabric showing my new design.

I claim:

The ornamental design for textile fabric, as shown.

ALOIS A. RITTER.
